UNITED STATES PATENT OFFICE.

NELSON W. DAVIS, OF PORT JEFFERSON, NEW YORK, ASSIGNOR OF ONE-HALF TO
LOPER BROTHERS, OF PORT JEFFERSON, NEW YORK.

PUMP.

1,146,312.

Specification of Letters Patent.

Patented July 13, 1915.

Application filed July 3, 1914. Serial No. 848,998.

To all whom it may concern:

Be it known that I, NELSON W. DAVIS, a citizen of the United States, residing at Port Jefferson, in the county of Suffolk and 5 State of New York, have invented a new and useful Pump, of which the following is a specification.

The present invention appertains to pumps, and relates more particularly to a 10 pump for Artesian or deep wells.

The present invention contemplates the provision of a novel and improved pump structure, adapted to be inserted down a well casing or pipe, and embodying unique means 15 for anchoring the cylinder of the pump in place within the well casing and for closing the space between the pump cylinder and well casing to prevent the collection of sediment or foreign matter therein.

20 Another object of the invention is to provide a stationary valve cage detachably engaged within the pump cylinder in a unique manner, in combination with a reciprocatory valve cage or piston mounted in the cylinder 25 above the stationary valve cage and having unique means engageable with the stationary valve cage, whereby the pump rod carrying the reciprocatory valve cage may be manipulated to properly insert and secure the 30 pump structure within the well casing, to remove the stationary valve cage, or to remove the entire pump structure from the well casing.

With the foregoing and other objects in 35 view which will appear as the description proceeds, the invention resides in the combination and arrangement of parts and in the details of construction hereinafter described and claimed, it being understood that changes 40 in the precise embodiment of the invention herein disclosed can be made within the scope of what is claimed without departing from the spirit of the invention.

The invention has been illustrated in its 45 preferred embodiment in the accompanying drawing, wherein—

Figure 1 is a longitudinal section of the pump as applied within a well casing. Figs. 2 and 3 are enlarged cross sections taken on 50 the lines 2—2 and 3—3, respectively, of

Fig. 1.

In carrying out the present invention, there is provided a tubular pump cylinder or sleeve 1, which is only slightly smaller in 55 diameter than the valve casing or pipe 2,

and which is insertable downwardly into the said casing. A nipple 3 is threaded into the lower end of the cylinder or sleeve 1, while a dog coupling or cuff 4 is threaded upon the lower end of the nipple 3. The nipple 3 is provided with right and left hand threads at its ends which engage the interior threads of the adjacent ends of the cylinder 1 and the coupling or cuff 4. A pair of looped dogs 45 have their ends riveted or otherwise secured within the lower end of the coupling or cuff 4, and are adapted to frictionally engage the interior of the well casing 2 to prevent the rotation of the coupling or cuff 4 when the pump structure is 70 inserted into the casing. Surrounding the intermediate portion of the nipple 3, is a compressible and expandable gasket or ring 6, of rubber or other suitable material, and the edges of which are adapted to abut or 75 rest against the adjacent ends of the cylinder 1 and coupling 4. The cylinder 1 is provided at its upper end with an outer annular rabbet 7, within which is secured or mounted a ring 8 of rubber or other expandable ma- 80 terial which will expand snugly within the casing 2 to close the upper end of the space between the cylinder 1 and casing 2.

A stationary valve cage or arched spider 9 is disposed within the lower end portion 85 of the cylinder or sleeve 1 directly above the nipple 3, and is provided with a lower annular valve seat 10, upon which a suitable valve 11 is normally seated. This valve 11 is confined within the cage or spider 9, 90 to move to and from the seat 10. The valve seat or lower annulus 10 of the valve cage 9 is equipped with a pair of diametrically opposite depending fingers 12 which are provided at their lower ends with oppositely 95 extending hooks 13 engageable under the inwardly projecting lugs 14 secured to diametrically opposite portions of the nipple 3.

A movable or reciprocatory valve cage or spider 15 is mounted within the cylinder 1 above the cage or spider 9, and has the lower end of the pump rod 16 attached to its crest portion. The cage or spider 15 is provided with the lower annulus or valve seat 17 upon which a suitable valve 18 is normally seated. 100 The valve 18 is confined within the cage or spider 15 to move to and from the valve seat 17. The valve seat or annulus 17 is equipped at diametrically opposite points with depending fingers 19 which are provided at 110

their lower ends with double hooks or T-heads 20. The independent hooks or arms of the double hooks or T-heads 20 are adapted to engage under the arched arms of the 5 cage or spider 9.

In assembling the parts of the pump, and in applying the pump within the valve casting 2, supposing the several parts to be detached or separated, the nipple 3 is first 10 threaded into the lower end of the cylinder 1 and the gasket or ring 6 placed upon the nipple. The coupling 4 is then threaded onto the lower end of the nipple 3, to such an extent, as to hold the gasket or ring 6 15 between the adjacent ends of the cylinder 1 and coupling 4 without spreading or expanding the gasket appreciably. The valve cage or spider 9 is then dropped into the cylinder 1 and manipulated so that the hooks 13 thereof engage under the lugs 14 of the nipple 3. Finally, the valve cage or spider 15 is inserted into the cylinder 1, and the T-heads 20 are passed between the arms of the cage or spider 9 and swung to engage 20 under certain of the said arms. The device is then inserted into the well casing 2 and forced downwardly therein to the point desired, the dogs 5 frictionally engaging the interior of the casing 2 and preventing the 25 rotation of the coupling or cuff 4. It is also to be observed that the expandable ring 8 secured to the upper end of the cylinder or sleeve 1 will expand snugly within the casing 2 to close the upper end of the space 30 between the cylinder 1 and casing 2. The pump rod 16 is then properly rotated, so as to rotate the valve cage or spider 9 in such a direction due to the engagement of the T-heads 20 with the cage or spider 9, to cause 35 the nipple 3 to be rotated for drawing the cylinder 1 and coupling 4 toward each other which will compress and expand the gasket 6 so that it engages tightly within the well casing 2. Thus, the gasket 6 closes the 40 lower end of the space between the cylinder 1 and the casing 2, and also assists in anchoring the cylinder within the well casing. The hooks 13 are so arranged, and the screw 45 threads of the upper and lower ends of the nipple 3 are such, that when the pump rod is rotated, as above noted, to expand the gasket 6, the hooks 13 will disengage the lugs 14, and the backs of the fingers 12 will come to rest against the lugs 14 when the 50 cage or spider 9 has rotated to one-half a revolution, to properly rotate the nipple 3 with the cage or spider 9 for the expanding of the gasket 6. The cage or spider 15 is then detached from the cage or spider 9, by 55 giving the pump rod 16 a slight turn, to disengage the T-heads 20 from the cage or spider 9, which will enable the cage or spider 15 to be raised and reciprocated for 60 operating the pump in the usual manner in 65 a device of the present character.

It is apparent that the reciprocatory cage or piston 15 may be withdrawn from the cylinder 1 and casing 2 at any time by lifting or elevating the pump rod 16. Should it be desired to also remove the stationary cage or spider 9, this may be readily accomplished by lowering the cage or spider 15 so that the T-heads or double hooks 20 project between the arms of the cage or spider 9. Then, by giving the pump rod 16 70 a proper turn to engage the T-heads or hooks 20 under the respective arms of the cage or spider 9, without engaging the hooks 13 with the lugs 14, the said cage or spider 9 may be elevated with the cage or spider 15 75 so as to be removed from the cylinder and well casing. Conversely, while the cage or spider 9 is engaged to the T-heads or hooks 20, the two cages or spiders may be simultaneously lowered into the well casing and 80 cylinder 1, to be replaced to their proper positions, as will be obvious from the foregoing.

When it is desired to remove the entire pump structure from the well casing, the 90 cage or spider 15 is first engaged to the cage or spider 9, as above indicated, and the pump rod 16 is then properly turned to rotate the cage or spider 9 in the proper direction to engage the hooks 13 under the lugs 14 of the nipple 3. Then, by lifting the 95 pump rod 16, the cage or spider 9 will not only be lifted by the cage or spider 15, but the nipple 3 and consequently the cylinder 1 and coupling 4 will be elevated therewith, 100 it being preferable, prior to the removal of the pump, to give the nipple 3 a few turns in the proper direction to loosen the coupling 4 slightly for enabling the gasket 6 to contract.

With the present pump, the cylinder 1 may occupy the greater portion of the space within the corresponding portion of the well casing 2, to reduce to a minimum the space between the cylinder 1 and the well 110 casing. It is also to be noted that the expandable ring 8 at the upper end of the cylinder 1, prevents the sediment or foreign matter from precipitating or accumulating within the space between the cylinder 1 and 115 well casing.

The present pump requires no special tools to insert or withdraw the several parts thereof, and the present pump reduces to a minimum, the amount of labor and time necessary for applying and removing the parts. The present invention also prevents the parts of the pump from being lost within the well casing and the present device is of advantage in other obvious respects, 120 which need not be enumerated.

Having thus described the invention, what is claimed as new is:

1. In a pump, a cylinder, a nipple threaded into the lower end thereof, a dog cou- 130

- pling threaded onto the lower end of the nipple, an expansible gasket surrounding the nipple between the adjacent ends of the cylinder and coupling, and a valve cage disposed within the cylinder directly above the nipple, the valve cage and nipple having interengageable means.
2. In a pump, a cylinder, a nipple threaded into the lower end thereof, a dog coupling threaded onto the lower end of the nipple, an expansible gasket surrounding the nipple between the adjacent ends of the cylinder and coupling, a valve cage disposed within the cylinder directly above the nipple, the nipple having inner lugs, and the valve cage having depending fingers provided with hooks at their lower ends engageable under the said lugs.
3. In a pump, a cylinder, a nipple threaded into the lower end thereof, a gasket carried by the nipple and adapted to bear against the lower end of the cylinder, a stationary valve cage mounted within the cylinder directly above the nipple, the nipple and stationary valve cage having means adapted to interengage when the cage is rotated in one direction, and a reciprocatory valve cage mounted within the cylinder above the stationary valve cage, the two valve cages having portions adapted to interengage when the reciprocatory valve cage is rotated in either direction.
4. In a pump, a cylinder, a nipple threaded into the lower end thereof, a gasket carried by the nipple and seatable against the lower end of the cylinder, and a valve cage mounted within the cylinder above the said nipple, the nipple having inwardly projecting lugs, and the valve cage having depending fingers provided with hooks at their lower ends engageable under the said lugs.
5. In a pump, a cylinder, a nipple threaded into the lower end thereof, a gasket carried by the nipple and seatable against the lower end of the cylinder, a stationary valve cage mounted within the cylinder above the said nipple, the nipple having inner lugs, and the stationary valve cage having depending fingers provided with hooks engageable under the said lugs, and a reciprocatory valve cage mounted within the cylinder above the stationary valve cage and having depending fingers provided with T-heads engageable with the stationary valve cage.
6. In a pump, a cylinder, an expansible gasket carried by the lower end thereof, means carried at the lower end of the cylinder for expanding the gasket, and an expansible ring carried by the upper end of the cylinder.

In testimony that I claim the foregoing as my own, I have hereto affixed my signature in the presence of two witnesses.

NELSON W. DAVIS.
